(57) **CLAIM**

The ornamental design for a carton with window, as shown and described.

DESCRIPTION

FIG. 1 is a perspective view of the carton with window, showing the present invention;

FIG. 2 is a front side view thereof;

FIG. 3 is a left side view thereof;

FIG. 4 is a top view thereof;

FIG. 5 is a rear side view thereof;

FIG. 6 is a right side view thereof; and,

FIG. 7 is a bottom view thereof.

The invention pertains to an ornamental design for an article of manufacture, which can be scaled to different sizes.
